UNITED STATES PATENT OFFICE.

JOHN J. ROBINSON, OF NEW YORK, N. Y.

NON-REFILLABLE BOTTLE.

1,171,141.

Specification of Letters Patent.

Patented Feb. 8, 1916.

Application filed February 2, 1915. Serial No. 5,681.

To all whom it may concern:

Be it known that I, JOHN J. ROBINSON, a citizen of the United States, residing in the city of New York, boroough and county of Bronx, in the State of New York, have invented a certain new and useful Improvement in Non-Refillable Bottles, of which the following is a specification.

The invention relates to that class of closures in which a spring actuated disk-valve is employed, and the object of the invention is to provide a simple and efficient device which may be economically manufactured and easily assembled, and which will permit the contained liquid to flow freely from the bottle, and effectually prevent refilling.

The invention consists in certain novel features and details of construction and arrangement by which the above objects are attained, to be hereinafter described and claimed.

The accompanying drawings form a part of this specification and show an approved form of the invention.

Figure 1 is a vertical axial section of a portion of a bottle-neck and the closure thereon. Fig. 2 is a top view with the cork removed. Figs. 3 and 4 are horizontal sections, partly in plan view, the planes of section being indicated by the lines 3—3 and 4—4 respectively. Fig. 5 is a plan view of the baffle-disk. Fig. 6 is a corresponding side elevation. Fig. 7 is a view of the under face of the same.

Similar letters of reference indicate the same parts in all the figures.

A is the upper portion of a bottle, constructed with a short neck A¹ on which the closure is mounted and shaped to form a continuation thereof. The closure comprises two main portions one above the other; on the neck A¹ is cemented the lower portion consisting of an annular shell B having a central opening b surrounded by a lip B¹ serving as a valve-seat for the disk-valve D, and having an annular channel b¹ exterior to the lip and below the latter. Above the shell B is the second portion or cap C having an annular skirt C¹ the lower face of which is applied upon and cemented to the shell B.

The cap has a pouring orifice, c closed by a cork G, connected by a contracted passage c¹ with a circular recess c² in the lower face having an annular shoulder or offset C² receiving the arms E¹ projecting from the

periphery of a baffle-disk E of larger diameter than the passage c¹, partially closing the recess c² and held centrally thereof by its arms which are cemented to the shoulder C². On the lower face of the baffle-disk is a depending annular flange or inverted cup E² terminating above the valve-seat B¹ and adjacent thereto.

The valve D has a stem D¹ extending downwardly through a guide or spider frame B² in the opening b, and a similar stem D² extending upwardly and axially of the cup E² is received in an axial hole in a boss E³ within the cup. A light delicate helical spring F encircles the portion D² of the valve-stem and is partially inclosed in the cup E²; it abuts within the latter at its upper end, and at the lower end upon the upper face of the valve D, tending by its slight expansive force to urge the valve to its seat.

When the cork G is removed and the bottle tilted the pressure of the valve D upon its seat, due to gravity, is lessened and the force of the liquid overcomes the resistance offered by the spring F, permitting the liquid to flow through the opening b to the annular space c⁴ exterior to the cup E², whence it passes through one or more of the passages c³ between the arms E¹ of the baffle-disk E to the recess c² and through the passage c¹ to the pouring orifice c. The movement of the liquid past the valve causes the latter to apply upon the edge of the cup E² as upon a valve-seat, and thus form a closed spring-chamber in which the spring is inclosed and contact of the liquid with the spring is prevented. To facilitate such sealing of the spring-chamber or cup, the valve D is provided on its upper face with an annular groove d matching the skirt or lip of the cup; and within the groove is an annular ridge D² forming a circular cavity of the same, or slightly smaller, diameter than the spring F and serving to engage the lower end of the latter. In attempting to refill the bottle the inflow of liquid, aided by the spring F, forces the valve to its seat and closes the opening b as will be understood, and the arrangement of the passages c³ with the baffle-disk E, relatively to the pouring orifice c and valve D, prevents tampering with the latter by the introduction of wires or other instruments through the pouring orifice. The annular channel b¹ serves as a recep-

tacle for the small quantity of liquid which flows back through the pouring passages when the bottle is restored to its upright position, and holds such liquid out of contact with the spring.

The parts B and C may be slightly conical or tapered externally, as shown, to simulate the usual form of bottle neck, and are joined to each other and to the neck A¹ of the bottle by a suitable cement, and these portions are preferably inclosed in a slightly tapered sleeve H of thin metal or heavy foil matching to and cemented thereon for purposes of reinforcement and ornamentation.

Importance is attached to the inverted cup E² and its coaction with the valve D in forming a closed chamber for the spring F during the pouring operation and thus avoiding contact of the liquid with such spring.

The shell B, cap C and valve D are preferably of porcelain or analogous material, and the spring F is of metal preferably non-corrosive in respect to the liquid contained in the bottle.

I claim:—

The improved non-refillable bottle herein described, comprising a shell having an

opening with a surrounding lip forming a valve seat and an annular channel exterior to and below said lip, a cap above said shell and having an annular skirt resting upon said shell, said cap having a pouring orifice with a contracted passage and an annular recess forming an annular shoulder, a baffle disk having arms engaging said shoulder, said baffle disk having a depending inverted cup terminating above said valve seat, a valve movable between the valve seat and the lower end of said cup and having upwardly and downwardly extended guiding stems, a guide within said shell for the lower stem and a guide within said cup for the upper stem, and a spring interposed between the cup and valve, said valve being adapted to be seated against said seat when in one position and to seat against the adjacent end of the cup when the resistance of the spring is overcome by the force of the liquid when the bottle is tilted.

In testimony that I claim the invention above set forth I affix my signature, in presence of two witnesses.

JOHN J. ROBINSON.
